UNITED STATES PATENT OFFICE.

WILLIAM H. HOOPER, OF LYNN, MASSACHUSETTS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

MACHINE FOR OPERATING ON AND MOISTENING PARTS OF SHOES.

1,291,888.

Specification of Letters Patent. Patented Jan. 21, 1919.

Application filed April 20, 1914. Serial No. 833,123.

To all whom it may concern:

Be it known that I, WILLIAM H. HOOPER, a citizen of the United States, residing at Lynn, in the county of Essex and State of Massachusetts, have invented certain new and useful Improvements in Machines for Operating on and Moistening Parts of Shoes; and I do hereby declare the following to be a full, clear, and exact description of the invention, such as will enable others skilled in the art to which it appertains to make and use the same.

This invention relates to machines for operating on the parts of shoes and more particularly to devices for moistening the leather before it is acted upon by the operating tool of the machine.

The invention is designed particularly to be applied to machines for indenting the leather to form imitation stitches and to machines for indenting the intervals between the stitches of a finished seam to separate the stitches. The invention is not, however, limited in its application to such machines, but certain features thereof may be embodied with advantage in other machines for operating upon the parts of shoes either before or after they are assembled upon a last.

The primary object of the invention is to provide machines for operating upon the parts of shoes with a moistening device for discharging a moistening liquid upon the leather to temper the same, in which the discharge of the moistening liquid is conveniently controlled without attention on the part of the operator so that the liquid is discharged upon the work while the work is operated upon by the tool and the discharge thereof is cut off when the work is removed from the machine.

Another object of the invention is to provide machines of this class with a moistening device by which the required amount of the moistening liquid may be discharged upon a certain desired portion of the work without wetting other portions thereof.

With these objects in view the invention comprises certain novel and improved constructions, arrangements and combinations of parts hereinafter described and particularly pointed out in the claims, the advantages of which will be obvious to those skilled in the art.

The features of the invention will be readily understood from the accompanying drawings and the following detailed description thereof in which is illustrated and described a machine embodying the invention in its preferred form.

The invention is illustrated in the drawings as applied to a machine for indenting the intervals between the stitches of the out-seam of a lasted shoe upon the upper surface of the projecting edge of the shoe sole.

In the drawings; Figure 1 is a view in front elevation of the machine; Fig. 2 is a detail view showing in longitudinal section of the nozzle of the moistening device and the adjacent connections; Fig. 3 is a sectional view taken substantially on the line 3-3 of Fig. 2; Fig. 4 is a sectional view taken substantially on the line 4-4 of Fig. 2; and Fig. 5 is a longitudinal sectional view of the nozzle of the moistening device taken in a plane substantially at right angles to the plane on which Fig. 2 is taken.

With the exception of the moistening device, the machine illustrated has the same general construction and mode of operation as the machine disclosed in the patent to Hadaway, No. 543,012, dated July 23, 1895. In the drawing, 2 indicates the indenting tool, 4 the tool stock upon which the indenting tool is mounted, 6 the lever upon which the tool stock is pivoted by means of the stud 8 secured in the lever, 10 the spring which acts on the lever 6 to engage the indenting tool lightly with the work, 12 the lever which actuates the lever 6 to raise the indenting tool from the work, and 14 the feed slide upon which the lever 6 is pivoted by means of the stud 16, and which is actuated to impart the locating and feeding movements to the indenting tool. All of the parts above mentioned have a construction, arrangement and mode of operation substantially the same as the corresponding parts of the machine illustrated and described in the Hadaway patent above referred to.

The presser lever for forcing the tool into the work is indicated at 18. This presser lever has substantially the same construction, and operates in substantially the same manner as the presser lever illustrated and described in the patent to Hadaway, No. 719,584, dated February 3rd, 1903.

The work is supported during the opera-

tion of the machine by means of a lower work support 20 which is pivotally mounted upon a stud 22 fixed in a vertically movable slide 24 mounted to slide in suitable guides in the forward portion of the machine. The lower work support is yieldingly supported by means of a spring 26 interposed between a lug 28 on the slide, and a washer engaging the upper end of a sleeve 30 threaded into a 5 forwardly projecting lug 32 upon the frame. A rod 34 having a head at its upper end passes through a suitable perforation in the lug 28 and through the sleeve 30, and the work support is depressed against the action 10 of the spring 26 by means of a treadle connected with the lower end of this rod. The construction and operation of the lower work support, the slide upon which it is mounted and the mechanism for supporting 15 and actuating the slide are substantially the same as in the machine shown and described in Hadaway Patent No. 543,012, and the machine illustrated is provided with means for locking and unlocking the slide during 20 each cycle of operations substantially the same as that disclosed in said patent.

The upper work support of the machine consists of two jaws indicated respectively at 36 and 38 extending forwardly upon each 30 side of the indenting tool. The jaw 36 of the upper work support is fixed and the jaw 38 is secured to the frame by means of a screw 40 passing through a slot in the block on which said jaw is formed so that it can 35 be adjusted toward and from the fixed jaw 36. The jaw 38 is adjusted toward and from the fixed jaw by means of the adjusting screws 44.

The moistening device by which the moistening liquid is discharged upon the work 40 before the work is acted upon by the indenting tool comprises a tank 46 mounted upon a standard 48 on the head of the machine and provided with an outlet pipe 50 having a stop cock 52 therein which is operated 45 by a thumb piece 54. The outlet pipe 50 is connected by means of a flexible pipe 56 with the upper extremity of a metal connection 58 which is threaded into a tubular 50 extension 60 on the member 38 of the upper work support, as shown particularly in Fig. 2. The bore 60^a in the tubular extension 60 extends downwardly through the lower face of the member 38, as clearly shown in this 55 figure, forming a discharge nozzle for the moistening device, the liquid being discharged upon the work through the lower end of the bore.

It will be noted that the discharge nozzle 60 of the moistening device is located just in advance of the indenting tool so as to discharge the moistening liquid upon the portion of the work to be acted upon by the tool just before it is presented to the tool. 65 In order to regulate the flow of the moisten-

ing liquid through the nozzle of the moistening device a needle valve 62 is threaded into the tubular extension 60, the tapered upper end of the valve engaging in a contracted portion of the pipe connection 58. 70 The opening between the contracted portion of this pipe connection and the tapered end of the needle valve may be varied by adjusting the valve in the extension 60. The enlarged lower threaded portion of the needle 75 valve is provided with a passage 64 for the moistening liquid as shown particularly in Fig. 3.

The moistening device is provided with a second valve which when the work support 80 is lifted by the spring 26 to bring the marginal portion of the projecting edge of the sole into position to be engaged by the indenting tool is opened so as to allow the moistening liquid to flow through the nozzle of the moistening device upon the work and is closed when the work support is depressed against the action of the spring. This valve, indicated at 66, is mounted in a suitable portion of the bore in the member 90 38 of the upper work support and is provided with a conical portion 68 which engages a suitably formed seat 70 in the adjacent wall of the bore. Adjacent the conical portion 68 the valve 66 is formed with a 95 groove indicated at 72 extending entirely about the same, and with a cross bore 74 extending diametrically through the valve. The cross bore 74 intersects and leads into the upper end of an axial bore 76 which at 100 its lower end intersects a second cross bore 78 which connects the axial bore 76 with a second groove 80 extending about the valve. A groove 82 cut in the face of the bore 60^a 105 in the member 38 on the side of said bore opposite the indenting tool forms a passage from the groove 78 to the lower face of said member. When the valve member 66 is lifted the moistening liquid flows between the conical portion 68 of the valve and the valve 110 seat 70 into the groove 72. From this groove the liquid then flows through the cross bore 74, the axial bore 76, the second cross bore 78, the groove 80 and the passage 82 to the work. The groove 82 is formed in the side 115 of the bore 60^a opposite the indenting tool so that the moistening liquid will be discharged upon the work a considerable distance in advance of the indenting tool and will be absorbed by the leather before it is acted upon 120 by the tool. The valve 66 is engaged by a coil spring 84 interposed between the upper end of the valve and the lower end of the needle valve 62 which acts to maintain the valve normally in closed condition so that 125 the flow of the moistening liquid to the work is cut off. As will be noted from an inspection of Figs. 2 and 5, the lower end of the valve 66 forms a plunger which extends below the lower surface of the member 38 of 130

the upper work support so that when the work is engaged with this projecting lower end of the valve the valve is opened.

The operation of the moistening device above described is as follows: When the operator is about to introduce the shoe in operative position he depresses the lower work support by means of the treadle connected with the rod 34 and then places the shoe upon the work support so that the projecting edge of the sole lies beneath the indenting tool. The treadle is then released and the lower work support is lifted by the action of the spring 26, bringing the upper surface of the projecting edge of the sole into engagement with the upper work support. During the upward movement of the lower work support the upper face of the projecting edge of the sole engages the projecting lower end of the valve 66 and lifts the valve, thereby allowing the moistening liquid to flow through the passage 82 on the work in advance of the indenting tool. During each cycle of operations of the machine the valve 66 is open during the locating movements of the indenting tool and when the indenting tool is forced down into the work. Just before the work is fed, however, the work support is unlocked and is then depressed slightly against the action of the spring 26 by the pressure of the indenting tool. The depression of the work support at this time is sufficient to remove the upper surface of the projecting edge of the sole from contact with the lower end of the valve 66 so that the valve is closed while the work is being fed. When the indenting operation is completed the operator depresses the treadle to enable the work to be removed, thereby lowering the shoe and removing the projecting edge of the sole from contact with the lower end of the valve 66, and the valve is then closed by the action of the spring 84. The moistening liquid which is discharged upon the leather before it is acted upon by the indenting tool serves to temper the same and enables the tool to indent the work more easily and results in rendering the indentation made in the leather more permanent. The valves which control the flow of the moistening liquid upon the work are constructed so that just the required amount of liquid will be discharged without wetting the upper of the shoe or any of the liquid flowing down over the edge of the sole. One or two drops of liquid discharged upon the work for each stitch is usually sufficient to suit the requirements for satisfactory work. Water, alcohol, or any other suitable moistening liquid may be used in this machine. If desired, moistening liquid may be heated before it is discharged upon the work by the flame from a gas jet 86 arranged adjacent the extension 60 so that the flame plays on said extension. The machine

has the decided advantages that all parts of the work along the line of operation are moistened uniformly and that the moistening operation is localized upon the portion of the work to be operated upon so that other portions thereof are not soiled and discolored by the moistening liquid.

Having explained the nature and object of the invention and having specifically described a machine embodying the features thereof in their preferred forms, what is claimed is:

1. A machine for operating upon the parts of shoes, having in combination, a device for operating on the work and a device for supporting the work while being operated on, one of which is movable to locate the work and the operating device in relative operating positions, a moistening device having a nozzle arranged to discharge a moistening liquid on the work, and a valve operated by the movement of the movable device for controlling the discharge of the moistening liquid through the nozzle.

2. A machine for operating on the parts of shoes, having in combination, an operating tool and a support for holding the work while it is operated on by the tool arranged for relative movement to place the work and the tool in relative operating positions, a moistening device having a nozzle arranged to discharge a moistening liquid on the work, and a valve operated by the relative movement of the work support and the tool for controlling the discharge of the moistening liquid through the nozzle.

3. A machine for operating on the parts of shoes, having in combination, work supporting devices arranged to engage opposite sides of the work and mounted for relative movement toward and from each other, a moistening device having a nozzle arranged to discharge a moistening liquid on the work, and a valve operated by the relative movement of the work supporting devices for controlling the discharge of liquid through the nozzle.

4. A machine for operating on the parts of shoes, having in combination, an indenting tool and a support for holding the work while it is operated on by the tool arranged for relative movement to place the work and the tool in relative operating positions, a moistening device having a nozzle arranged to discharge a moistening liquid on the work, and a valve operated by the relative movement of the work support and the tool to place the tool and the work in relative operating positions for controlling the discharge of the moistening liquid through the nozzle.

5. A machine for operating on the parts of shoes, having in combination, an indenting tool and a support for holding the work

- 4
- while it is operated on by the tool arranged for movement relative to the indenting tool to place the work in operating position with relation to the tool, means for raising and 5 lowering the work support, a moistening device having a nozzle arranged to discharge a moistening liquid upon the work, and a valve arranged to be opened by the upward movement of the work support and to be closed when the work support is depressed. 10
6. A machine for operating on the parts of shoes, having, in combination, an indenting tool, means for actuating the tool to find the intervals between the stitches of a 15 seam and to indent the intervals to separate stitches, a moistening device having a nozzle arranged to discharge a moistening liquid on the work, a valve for controlling the discharge of the moistening liquid through the 20 nozzle, and means for opening the valve during the locating and indenting movements of the tool and for closing the valve while the work is fed. 25
7. A machine for operating on the parts of shoes, having in combination, an indenting tool, means for actuating the tool to indent the intervals between the stitches of a seam, a moistening device having a nozzle arranged to discharge a moistening liquid 30 on the work, a valve for controlling the discharge of the moistening liquid through the nozzle, and means for opening and closing the valve during each cycle of operations. 35
8. A machine for operating on the parts of shoes having, in combination, a moistening device for discharging a moistening liquid upon the stock arranged to permit a part of a shoe to be presented thereto, means for controlling the discharge of the moistening liquid through the nozzle, and mechanism 40 for applying heat directly to the nozzle to heat the same so that the moistening liquid will be discharged from the nozzle at a relatively high temperature. 45
9. A machine for operating upon the parts of shoes, having, in combination, a work support and a presser-foot relatively movable toward and from each other, a moistening device having a nozzle arranged to discharge a moistening liquid upon the work, 50 and a valve for controlling the discharge of the moistening liquid through the nozzle, arranged to be opened by the relative movement of the work support and presser-foot toward each other and to be closed upon the 55 relative movement of the work support and presser-foot away from each other. 60
10. A machine for operating upon the parts of shoes, having, in combination, a work support and a presser-foot relatively 65 movable toward and from each other, a moistening device having a nozzle for discharging a moistening liquid upon the work, and valve mechanism for controlling the discharge of the moistening liquid through 70 the nozzle comprising a movable device mounted on the presser-foot and arranged to be engaged by the work and to be actuated to open the valve during the relative movement of the work support and presser- 75 foot toward each other. 80
11. A machine for operating upon the parts of shoes, having, in combination, work engaging devices arranged to engage opposite sides of the work and mounted for relative movement toward and from each other, a moistening device having a nozzle arranged to discharge a moistening liquid on the work, and valve mechanism for controlling the discharge of the moistening liquid 85 through the nozzle, comprising a device arranged to engage the work and to be operated to open the valve by the relative movement of the work-engaging devices toward each other. 90
